UNITED STATES PATENT OFFICE.

BUTLER AMES AND PHILIP J. GILINSON, OF LOWELL, MASSACHUSETTS; SAID GILINSON ASSIGNOR TO SAID AMES.

ELECTRICAL CONDENSER.

Application filed February 15, 1918. Serial No. 217,441.

To all whom it may concern:

Be it known that we, BUTLER AMES and PHILIP J. GILINSON, both citizens of the United States, and residents of Lowell, in the county of Middlesex and Commonwealth of Massachusetts, have invented new and useful Improvements in Electrical Condensers, of which the following is a specification.

10 This invention relates to electrical condensers and has for its object a condenser which is simple to construct, which is compact in form, which can be tightly compressed to expel any air trapped therein, 15 which will fit into a magneto rotor or other restricted space, which has a large area of contact between the layers of conducting material and the terminals, whose layers of insulating material are symmetrical and 20 perforate, whose layers of conducting material are imperforate and formable from a band or ribbon of material, whose parts are secured together by means not extending through the alternate layers of insulating 25 and conducting material, and which is of generally improved construction. While all of the above objects are attained in the preferred embodiment of our invention it is to be understood that certain of these objects 30 may be attained independently in so far as certain aspects of the invention are concerned.

According to the present invention the layers of insulating material are preferably 35 of substantially square formation while the layers of conducting material are somewhat longer and somewhat more narrow than the insulating sheets so that a conducting sheet placed centrally upon an insulating sheet 40 will project beyond the insulating sheet at its opposite ends but will be confined within the limits of the insulating sheet at its sides. In building up the condenser layers the alternate layers of conducting material are 45 disposed at right angles to each other so that every other layer of conducting material projects from one pair of opposite sides of the insulating sheets and the intermediate layers of conducting material project 50 from the other pair of opposite sides of the insulating sheets. The projecting ends of each set of conducting sheets are utilized to connect the sheets to terminal plates or other suitable termi-

nals, as by folding the projecting ends over 55 each other and soldering them to the terminals, and both ends of each sheet are preferably connected to a terminal so that the current may surge to and from the conducting sheets more rapidly. The alternate 60 conducting and insulating sheets are preferably compressed between two plates, which may be the terminal plates, and the plates are preferably connected together by suitable means disposed in the four corners 65 between the projecting ends of the conducting sheets.

In the accompanying drawings,—

Figure 1 is an end view of a device embodying our invention;

Figure 2 is an end view of the device showing the opposite end;

Figure 3 is a side elevation of the device;

Figure 4 is a central section on line 4—4 of Fig. 1;

Figure 5 is a section on line 5—5 of Fig. 3;

Figure 6 is a perspective view of the device; and

Figure 7 is a perspective view of the 80 interior portion of a modified device embodying our invention.

The device illustrated in Figs. 1 to 6 essentially comprises a body portion 1 made up of alternate layers of insulating and conducting material, end plates 2 and 3 disposed at opposite ends of the body portion, and rivets 4 for securing the end plates together.

The insulating layers of the body portion 90 are in the form of square sheets 5 having their corners cut off as shown at 6 in Fig. 5. The conducting layers are in the form of oblong sheets alternate ones of which are disposed at right angle to each so as to form 95 two sets of conducting sheets 7 and 8 angularly displaced from each other 90° as indicated in Fig. 5. The conducting sheets extend somewhat beyond the opposite sides of the insulating sheets and at each side are 100 folded over each other and pressed together with a hot iron or otherwise connected together as indicated at 9, 9^a, 10 and 10^a in Figs. 3 to 6. While these are the preferred shapes of the insulating and conducting 105 sheets it is to be understood that the shapes may be varied within the scope of the invention in its broader aspect so long as the

conducting layers project from different sides of the condenser so as to be united together.

The end plates 2 and 3 are insulated from the body portion 1 by layers of insulation 11 and 12 and the rivets 4 are insulated from the end plate 2 by insulating washers 13 and bushings 13^a. Extending from plate 2 along one pair of opposite sides of the condenser 10 are two flanges 14 and 14', these flanges contacting respectively with the ends of the set 7 of conducting sheets; and extending from plate 3 along the other pair of opposite sides of the condenser are two flanges 15 and 16, these flanges contacting respectively with the ends of the set 8 of conducting sheets. A film of solder is preferably flowed in between each of these flanges and the corresponding set of ends of the conducting sheets to insure a perfect contact between each end of each conducting sheet and one of the end plates. When the end plates are utilized as terminal plates they are provided with terminal lugs 17 and 18, respectively, 25 to which circuit leads may be connected.

Lugs 19 and 20, extending outwardly from the flanges 15 and 16 of plate 3, serve to mount the condenser as shown for example in the application of Butler Ames, Sr. 30 No. 217,468, filed on even date herewith. The plate 2 is provided with a tubular projection 21 extending outwardly from the center thereof, the projection being tapped to receive a screw for attaching the condenser 35 to other apparatus as disclosed for example in said copending application.

In Figure 7 we have illustrated a modification in which the body portion 1 of the condenser is bound together by two bands 40 22 and 23 of copper or other conducting material, after which it may be employed thus or between end plates as above described. The bands 22 and 23 are insulated from each other by insulation sheets 24, from 45 the conducting layers, except at the ends 9' and 10', by insulation sheets 25 similar to sheet 5 in Fig. 5. The ends of the bands are lapped as shown, preferably on the same side of the body 1.

50 The preferred method of constructing the body portion of our improved condenser is as follows: The layers of conducting material 7 and 8 are preferably supplied in the form of a ribbon, lengths of the ribbon sufficient to form the sheets being cut off as the condenser is built up. Two separate spools of ribbon may be employed, the two spools being respectively mounted near adjacent sides of the condenser or near adjacent sides 55 of a frame having four corner posts spaced the same as posts 4, in either case of which the set of sheets 7 is obtained from one spool and the set 8 from the other spool. However, it is deemed preferable to employ a 60 single spool and mount the condenser or 65

assembling frame to oscillate back and forth about its axis through an angle of 90° so that a sheet 7 may be applied when in one extreme position and a sheet 8 when in the opposite position.

70 From the foregoing description read in connection with the accompanying drawings the advantages of our improved construction will be apparent. The disposition of the oblong conducting sheets between the four corner posts renders the construction of the apparatus simple and facile. Owing to the fact that the means for connecting the terminal plates together do not pass through the body portion of the condenser but are 75 located in the corners between the ends of the sets of conducting sheets, the body portion may be completely built up and compressed before being clamped between the terminal plates, the connecting means do not 80 extend outside the ends of the conducting sheets, and there is no liability of short circuiting the conducting sheets through the connecting means. The flanges on the end 85 plates serve to enclose and protect the body portion, to afford a conducting path between the conducting layers and end plates and to carry the terminal connectors. And by virtue of the conducting path between each 90 end of each conducting sheet and the corresponding terminal plate throughout the entire width of the sheet the condenser may 95 charge and discharge more rapidly and efficiently.

100 We claim:

1. An electrical condenser comprising alternate layers of conducting and insulating material, the layers of conducting material being somewhat longer than wide and alternate layers of the conducting material 105 being disposed transversely of each other so as to project laterally on each side, and means disposed at least in part in the corners between the projecting ends for holding the 110 layers together.

2. An electrical condenser of the type having a plurality of plates separated by a dielectric, the condenser being characterized in that the plates have projections extending outwardly from the sides thereof, the 115 projections from certain plates at recurrent intervals extending from one side of the condenser and the projections from certain other plates at recurrent intervals extending from another side of the condenser, and end 120 members extending substantially across the condenser along the ends thereof parallel to said layers, one of the end members being connected to said projections at one side of the condenser and the other end member being connected to said projections on the other side of the condenser.

3. An electrical condenser comprising alternate sheets of insulating and conducting material, the alternate conducting sheets 125

being disposed at right angles to each other and extending beyond the sides of the insulating sheets at both ends, and a terminal member extending across the end of the 5 condenser and contacting with the opposite ends of each set of conducting sheets.

4. An electrical condenser comprising alternate sheets of insulating and conducting material, the conducting sheets being divided 10 into two sets respectively comprising alternate sheets of the conducting material, one set of conducting sheets extending beyond one pair of opposite sides of the insulating sheets and the other set of conducting sheets 15 extending beyond the other pair of opposite sides of the insulating sheets, and a terminal member contacting with the opposite ends of each set of conducting sheets.

5. An electrical condenser comprising 20 alternate sheets of insulating and conducting material, the conducting sheets being divided into two sets respectively comprising alternate sheets of the conducting material, one set of conducting sheets projecting beyond 25 one pair of opposite sides of the insulating sheets and the other set of conducting sheets projecting beyond the other pair of opposite sides of the insulating sheets, the projecting portions of each set of conducting 30 sheets being folded over at each end, and a terminal member extending across the end of the condenser and contacting with the folded portions of each set at both ends.

6. An electrical condenser comprising 35 alternate sheets of insulating and conducting material, the conducting sheets being divided into two sets respectively comprising alternate sheets of the conducting material, one set of conducting sheets extending 40 beyond one pair of opposite sides of the insulating sheets and the other set of conducting sheets extending beyond the other pair of opposite sides of the insulating sheets, and end members having opposed portions 45 extending along said pairs of sides respectively in electrical contact with the opposite ends of each set of conducting sheets.

7. An electrical condenser comprising 50 alternate sheets of insulating and conducting material, the conducting sheets being divided into two sets respectively comprising alternate sheets of the conducting material, one set of conducting sheets projecting beyond one pair of opposite sides of the 55 insulating sheets and the other set of conducting sheets projecting beyond the other pair of opposite sides of the insulating sheets, and means disposed in the corners between the projecting ends of the respective sets of conducting sheets for securing 60 said end members together.

8. An electrical condenser comprising 65 alternate sheets of insulating and conducting material, the insulating sheets having substantially the same width as length and

the conducting sheets being somewhat longer and narrower than the insulating sheets, and the alternate conducting sheets being disposed transversely of each other and extending beyond the edges of the insulating 70 sheets, and end plates having flanges extending into contact with the alternate sets of said edges respectively, the flange of one plate contacting with one set and the flange of the other plate contacting with the other 75 set.

9. An electrical condenser comprising substantially square sheets of insulating material, oblong sheets of conducting material, the latter sheets being longer and narrower 80 than the former sheets and being alternately disposed transversely of each other with their opposite ends projecting beyond the opposite edges of the insulating layers, end plates disposed on opposite sides of said 85 sheets, each end plate having portions on opposite sides thereof contacting with said projecting ends of certain of the conducting sheets, and posts for securing said end plates together, the corners of the insulating sheets being cut away and said posts being disposed in the cut-away corners between the projecting ends of the conducting sheets.

10. An electrical condenser comprising alternate sheets of insulating and conducting material, the conducting sheets being longer and narrower than the insulating sheets and being alternately arranged transversely of each other so as to form two angularly 95 spaced sets of sheets, the ends of one set of sheets projecting from one pair of opposite sides of the condenser and the ends of the other set of sheets projecting from the other pair of opposite sides of the condenser, a 100 body of conducting material disposed around said alternate sheets in electrical contact with the opposite ends of one set of sheets, and a second body of conducting material disposed around said alternate sheets in 105 electrical contact with the opposite ends of the other set of sheets.

11. An electrical condenser comprising alternate sheets of insulating and conducting material, the conducting sheets being 115 divided into two sets respectively comprising alternate sheets of the conducting material, one set of conducting sheets projecting beyond one side of the insulating sheets and the other set of conducting sheets projecting 120 beyond another side of the insulating sheets, and end plates disposed at opposite ends of said sheets in planes substantially parallel with the planes of the sheets, said end plates having flanges extending along 125 said sides in electrical contact with the projecting ends of said sets respectively.

12. An electrical condenser comprising sheets of conducting material, sheets of insulating material interposed between the 130

conducting sheets, and a stiff end clamping plate of conducting material disposed in a plane substantially parallel with the planes of said sheets, the ends of alternate conducting sheets extending beyond the edges of the insulating sheets into electrical contact with said clamping plate.

13. An electrical condenser comprising sheets of conducting material, sheets of insulating material interposed between the conducting sheets, and a stiff end clamping plate of conducting material disposed in a plane substantially parallel with the planes of said sheets, the ends of alternate conducting sheets extending beyond the edges of the insulating sheets and being soldered directly to said end plate.

14. An electrical condenser comprising sheets of conducting material, sheets of insulating material interposed between the 20 conducting sheets, and a stiff end plate of conducting material disposed in a plane substantially parallel with the planes of said sheets, said end plate having a flange extending along the edges of said sheets at 25 one side of the condenser in electrical contact with recurrent sheets of conducting material.

Signed by BUTLER AMES at Boston, Mass., this 5th day of February, 1918, and by 30 PHILIP GILINSON, at Lowell, Mass., this 5th day of February, 1918.

BUTLER AMES,
PHILIP J. GILINSON.
